BOTTLE

Nathan B. Lerner, Chicago, Ill., assignor to
W. Braun Company, Chicago, Ill.

Filed Oct. 20, 1971, Ser. No. 191,154

Term of patent 14 years

Int. Cl. D9—01

U.S. Cl. D9—143

FIG. 1 is a perspective view of a bottle showing my new design;

FIG. 2 is a side elevational view thereof;

FIG. 3 is a top plan view thereof;

FIG. 4 is an end elevational view thereof;

FIG. 5 is a bottom plan view thereof; and

FIG. 6 is a sectional view taken on line 6—6 of FIG. 2.

I claim:

The ornamental design for a bottle, as shown.
